[57] CLAIM

The ornamental design for a skin for vacuum sweeper, substantially as shown and described.

DESCRIPTION

FIG. 1 is a plan view of a skin for a vacuum sweeper embodying the present design; and FIG. 2 is a skin for a vacuum sweeper illustrating a modified form of the present invention. The undisclosed sides of FIGS. 1 and 2 are mirror images of the respective sides shown. The skin is of no substantial thickness. The nondescript lines on the surface of the design of FIG. 2 represent the surface of leather-like material.
